(57) **CLAIM**

The ornamental design for a golf club head, as shown and
described in the accompanying drawings.

DESCRIPTION

FIG. 1 is a perspective view of the golf club head;
FIG. 2 is a right side view of the golf club head;
FIG. 3 is a left side view of the golf club head (the left side
view is unadorned);

FIG. 4 is a rear view of the golf club head;

FIG. 5 is a front view of the golf club head;

FIG. 6 is a top view of the golf club head; and,

FIG. 7 is a bottom view of the golf club head.

The broken line showing depicts environmental subject matter
only and forms no part of the claimed design.
